ADJUSTABLE SPLINED PINION

Robert J. Eninger, Kendallville, Ind., assignor to Fort Wayne Tool and Die, Inc., Fort Wayne, Ind.
Filed Dec. 14, 1960, Ser. No. 75,733
7 Claims. (Cl. 287—53)

This invention relates generally to the combination of a splined shaft and a member for guiding the shaft for longitudinal movement while imparting rotary motion thereto, and more particularly to an adjustable splined pinion incorporating means for removing back-lash from the splined shaft.

In Patent 2,847,170 issued to John F. Lill and the present applicant on August 12, 1958, assigned to the assignee of the present application, stator winding apparatus is disclosed incorporating a winding head which is caused to move through the bore of the stator being wound in a generally rectilinear path in order to wind coils in the stator slots. This rectilinear motion of the winding head is provided by mounting the winding head upon a splined shaft which is guided for longitudinal movement and simultaneously rotated by a splined pinion.

In winding apparatus of the type disclosed in the aforementioned patents, it is necessary, particularly when winding stators having narrow slots, that back-lash of the splined shaft be completely eliminated. In the past, both the splined shaft and splined pinion have been formed of hardened steel and close manufacturing tolerances were required both in cutting the splines in the pinion and on the shaft in order to provide minimum initial back-lash. Winding machines of the type disclosed in the aforementioned patent operate at a relatively high speed and thus, both the steel shaft and steel pinion are subject to rapid wear in turn requiring frequent replacement in order to maintain the requisite minimum back-lash. Further, with the previously employed steel shaft and pinion, the close fit required for minimum back-lash purposes caused the splined shaft to seize at high speeds.

It is therefore desirable to provide a splined pinion which may be adjusted both initially and from time to time as wear occurs in order to remove all backlash from the splined shaft.

It is an object of my invention to provide adjustable guiding means for a splined shaft.

Another object of my invention is to provide an adjustable splined pinion for a splined shaft.

Further objects and advantages of my invention will become apparent by reference to the following description and the accompanying drawing, and the features of novelty which characterize my invention will be pointed out with particularity in the claims annexed to and forming a part of this specification.

My invention in its broader aspects provides an externally splined shaft and an internally splined device for accommodating relative longitudinal motion of the shaft. The internally splined device comprises first and second relatively rotatable parts each having an internally splined portion with the shaft passing therethrough. The first and second parts have adjacent facing surfaces which are respectively coaxial with the shaft, the first part surface having a first annular groove formed therein coaxial with the shaft and the second part surface having a second groove formed therein coaxial with the shaft and forming part of an annulus, the grooves being concentric and mutually defining a cavity. The first part has an opening therein communicating with the cavity and force transferring means are positioned in the cavity having one end engaging one end of the second groove and its other end facing the opening in the first part. Adjustable means are provided in the opening and having a portion extend-

2

ing into the cavity and engaging the other end of the force transferring means whereby force exerted on the other end of the force transferring means is applied to the one end of the second groove thereby tending to rotate the second part with respect to the first part and in turn causing the splined portions to engage the shaft in order to prevent rotational movement of the shaft with respect to the device.

In the drawing:

10 FIG. 1 is a fragmentary view illustrating the employment of my invention in a winding machine of the type disclosed in the foregoing patent;

15 FIG. 2 is a fragmentary cross-sectional view illustrating the adjustable splined pinion of my invention;

FIG. 3 is a top view of my adjustable splined pinion taken along the line 3—3 of FIG. 2;

FIG. 4 is a cross-sectional view taken along line 4—4 of FIG. 2;

20 FIG. 5 is a cross-sectional view taken along the line 5—5 of FIG. 2;

FIG. 6 is a cross-sectional view taken along the line 6—6 of FIG. 2; and

FIG. 7 is a side view of the inner splined section of the splined pinion of FIG. 2.

25 Referring now to the drawings, there is shown a winding head 10 having conventional wire dispensing needles 12 extending therefrom. Winding head 10 is carried by a splined shaft 14 through which wire 16 is fed for dispensing through the needles 12 and into the slots of an internally slotted dynamoelectric machine stator core member (not shown) as winding head 10 is reciprocally moved through the stator bore. The reciprocal motion is imparted to splined shaft 14 and winding head 10 by

30 means of a drive shaft 18, carrying a crank 20 and pitman 22 pivotally connected to crank 20 and to the splined shaft as at 24. It will be readily apparent that as the drive shaft 18 is rotated by the driving motor of the winding apparatus (not shown), crank 20 and pitman 22 will impart linear reciprocal motion to the winding head 10 and splined shaft 14.

35 Winding head 10 and splined shaft 14 are rotated at the ends of their reciprocal stroke, respectively, by means of an internally splined pinion, generally identified at 26, which guides the splined shaft 14 in its reciprocal motion and which imparts rotary motion thereto. A barrel cam 28 is provided mounted on shaft 18 and rotated therewith and having a cam slot 30 formed therein. A cam follower 32 rides in the cam slot 30 and is carried by arm 34 pivoted as at 36. Arm 34 is in turn pivotally connected at 38 to rack 40 which engages teeth 42 of splined pinion 26. Splined pinion 26 has journal surfaces 44 and 46 formed thereon respectively journaled in bearing elements 48 and 50 which are secured to the winding apparatus.

40 Referring now to FIGS. 2 through 7 of the drawing, adjustable splined pinion 26 comprises two relatively rotatable splined sections 52 and 54. Section 52 is elongated and has a cylindrical pocket extending inwardly from its end 56 with its side wall 58 coaxial with and radially spaced from splined shaft 14 and with its bottom wall 60 extending radially outwardly from shaft 14.

45 Internal splines 62 are formed on member 52 for guiding shaft 14 for reciprocal movement in the direction shown by the arrows 64, the splines 62 communicating with the bottom wall 60 of the pocket and with an elongated opening 66 extending to the other end 68 of member 52 which coaxially surrounds shaft 14.

50 Pinion teeth 42 are formed on the exterior of member 52 in order to impart the requisite rotational motion thereto and in turn to shaft 14. Member 52 is preferably formed of a good bearing material, such as bronze in order to prevent seizing at high speed, and thus, steel

55

60

65

70

journal sleeves 44 and 46 are pressed thereover in order rotatably to support the member 52.

Splined section 54 is cylindrical in configuration and is journaled within the pocket member 52 so as to be relatively rotatable with respect to the member 52; splined section 54 has its cylindrical side wall 70 in sliding engagement with side wall 58 of the pocket and its bottom wall 72 likewise in sliding engagement with bottom wall 60 of the pocket. Splined section 54 has internal splines 74 formed therein which also cooperate with the externally splined shaft 14 to guide the same for longitudinal movement.

The outer periphery of member 52 adjacent end 56 is enlarged, as at 76, and an annular groove 78 of semicircular cross-section is formed in side wall 58 of the pocket member 52, as shown. Another groove 80 of semicircular cross-section and defining part of an annulus is formed in the outer side wall 70 of splined section 54, the grooves 78 and 80 being concentric and mutually defining a cavity 82 of circular cross-section. A boss or projection 84 is formed on one side of the enlarged portion 76 of member 52 and has an opening 86 formed therein tangentially communicating with the cavity 82 and coplanar therewith. Opening 86 is internally threaded to receive threaded plug 88 which has a projection 90 formed thereon extending into the cavity 82; plug 88 is provided with a socket 92 whereby the plug with its projection 90 may be threaded into and out of opening 86. A chain of balls 94 is provided respectively abutting and substantially filling cavity 82, one end ball 96 engaging the end 98 of slot 80 in splined section 54, and the other end ball 100 facing the opening 86, but being nevertheless outside of the opening 86 so that an equator of ball 100 continuously engages the wall of cavity 82. Projection 90 of plug 88 engages the end ball 100 thus biasing the balls 94 into abutting relationship so that the end ball 96 engages end 98 of groove 80.

It will now be readily seen that if there is any initial back-lash provided between the splined shaft 14 and the splined members 52 and 54, this back-lash can immediately be taken up and completely eliminated by adjustment of plug 88 further into opening 86 so that projection 90 forces the chain of balls 94 and the end ball 96 against end 98 of splined section 54 thereby tending to rotate section 54 in the direction shown by the arrow 102 with respect to member 52. This rotation of splined section 54 in the direction shown by the arrow 102 causes the side walls 104 of splines 74 to engage the corresponding sides 106 of the external splines 108 of splined shaft 14 thus tending to rotate splined shaft 14 in the direction shown by the arrow 110. Rotation of the splined shaft 14 in the direction shown by the arrow 110 in turn causes the sides 112 of splines 108 to bear against the corresponding sides 114 of splines 62 of the member 52, thus completely eliminating all initial back-lash. It will further be seen that by virtue of the fact that the members 52 and 54 are formed of bearing materials, such as bronze, reciprocation of the splined shaft 14 and splines 62 and 74 will cause wearing of these splines rather than wearing of the harder splines 108 of the steel splined shaft 14. However, as wear occurs in the splines 62 and 74 of splined sections 52 and 54, adjustments of plug 88 can be made repeatedly in order to take up the resulting back-lash in the manner just described.

The provision of the projection 90 on the plug 88 is an important feature of my invention since it is necessary that the end ball 100 be completely within the cavity 82 and outside of the opening 86 with its equator thus completely engaging the wall of cavity 82; if the end ball 100 is allowed to move into opening 86, it will be seen that its equator will not completely engage the inner wall of cavity 82 and thus the end ball 100 can move transversely as well as in the direction of the cavity 82

and thus can become wedged in the enlarged region 116 defined by opening 86 and groove 80 thus preventing further adjustment, scoring the surface of groove 80, and requiring disassembly of the splined pinion.

It will be seen that with my adjustable splined pinion, the close manufacturing tolerances previously required in cutting the spline in the pinion and on the shaft are no longer necessary since the ability to adjust the relative rotational positions of splined sections 52 and 54 permits initial adjustment to eliminate all back-lash in the splined shaft 14. Further, with the adjustable feature of my invention, the splined members 52 and 54 may be formed of material having good bearing properties rather than of steel and thus my adjustable splined pinion can accommodate higher linear speeds of shaft 14 without seizing.

While my adjustable splined pinion has particular utility in the winding machines of the aforementioned patent, it will be seen that it may be employed in any arrangement in which an externally splined shaft moves through an internally splined member.

While I have illustrated and described a specific embodiment of my invention, further modifications and improvements will occur to those skilled in the art and I desire therefore in the appended claims to cover all modifications which do not depart from the spirit and scope of my invention.

What is claimed is:

1. In combination; an externally splined shaft; and an internally splined device for accommodating relative longitudinal motion of said shaft with respect to said device, said device comprising first and second relatively rotatable parts each having an internally splined portion with said shaft passing therethrough, said parts having adjacent facing surfaces which are respectively coaxial with said shaft, said first part surface having a first annular groove formed therein coaxial with said shaft, said second part surface having a second groove formed therein coaxial with said shaft and forming part of an annulus, said grooves being concentric and mutually defining a cavity, said first part having an opening therein communicating with said cavity, force transfer means in said cavity having one end engaging one end of said second groove and its other end facing said opening, and adjustable means in said opening and having a portion extending into said cavity and engaging the other end of said force transfer means whereby force exerted on said other end of said force transfer means is applied to said one end of said second groove thereby tending to rotate said second part with respect to said first part causing said splined portions to engage said shaft to prevent rotatable movement thereof with respect to said device.

2. The combination of claim 1 wherein a pinion is formed on one of said parts for rotating said shaft.

3. The combination of claim 1 wherein said force transfer means comprises a plurality of separate but abutting elements.

4. The combination of claim 1 wherein said cavity has a circular cross-section, and wherein said force transfer means comprises a plurality of abutting balls substantially filling said cavity.

5. In combination; an externally splined shaft; and an internally splined device for accommodating relative longitudinal motion of said shaft with respect to said device, said device comprising first and second relatively rotatable parts each having an internally splined portion with said shaft passing therethrough, said parts having adjacent facing surfaces which are respectively coaxial with said shaft, said first part surface having a first annular groove formed therein coaxial with said shaft, said second part surface having a second groove formed therein coaxial with said shaft and forming part of an annulus, said grooves being concentric and mutually defining a cavity having a circular cross-section, said first part having an opening formed therein tangentially communicating with

said cavity and coplanar therewith, a chain of abutting balls in said cavity substantially filling the same with one end ball abutting the one end of said second groove remote from said opening and the other end ball facing but outside of said opening, and a plug adjustably seated in said opening for longitudinal movement therein and having an extension portion projecting into said cavity and engaging the other end ball whereby force exerted on said chain of balls by said plug extension is applied to said one end of said second groove thereby tending to rotate said second part with respect to said first part causing said splined portions to engage said shaft to prevent rotatable movement thereof with respect to said device.

6. In combination: an externally splined shaft; a first member coaxially surrounding said shaft and having a first internally splined portion cooperating with said shaft for accommodating relative longitudinal movement thereof, said first member having a cylindrical pocket formed in one end with its side wall coaxial with said shaft; a cylindrical member journaled in said pocket for rotation relative to said first member and having its side wall closely adjacent the side wall of said pocket, said cylindrical member having a second internally splined portion cooperating with said shaft for accommodating relative longitudinal movement thereof; said side wall of said pocket having a first annular semi-circular groove formed therein, said side wall of said cylindrical member having

5 a second semi-circular groove formed therein forming part of an annulus, said grooves being concentric and mutually defining a cavity having a circular cross-section; said first member having an opening formed therein tangentially communicating with said cavity and coplanar therewith; a chain of abutting balls in said cavity substantially filling the same with one end ball abutting the one end of said second groove remote from said opening and the other end ball facing but outside of said opening; and a plug adjustably threaded in said opening for longitudinal movement therein and having an extension portion projecting into said cavity and engaging the other end ball whereby force exerted on said chain of balls by said plug extension is applied to said one end of said second groove thereby tending to rotate said cylindrical member with respect to said first member causing said splined portions to engage said shaft to prevent rotation movement thereof with respect to said member.

10 15 20 7. The combination of claim 6 wherein a pinion is formed on the outer surface of said first member for rotating said shaft.
